UNITED STATES PATENT OFFICE.

LEAMON G. SOUDER, OF PHILADELPHIA, PENNSYLVANIA.

MOVING SPIRAL STAIRWAY OR ELEVATOR.

SPECIFICATION forming part of Letters Patent No. 792,623, dated June 20, 1905.

Application filed October 25, 1904. Serial No. 229,922.

To all whom it may concern:

Be it known that I, LEAMON G. SOUDER, a citizen of the United States, residing at the city of Philadelphia, in the county of Philadelphia and State of Pennsylvania, have invented certain new and useful Improvements in Moving Spiral Stairways or Elevators, of which the following is a specification.

My invention has relation to a moving stairway or elevator, and in such connection it relates more particularly to an improvement upon the moving stairway and elevator illustrated and described in United States Letters Patent No. 723,325, granted to me under date 15 of March 24, 1903, the present improvements residing in sectional risers constituting, in conjunction with segmental treads, the stairway or elevator adapted to ascend or descend in spiral courses in step-like form and to be flexed, 20 so as to assume a belt-like form in a horizontal plane.

The principal object of my invention is to provide in a moving stairway or elevator a divided or sectional riser, each section of 25 which is hinged to a tread and both sections pivotally connected with each other at one end to allow the risers to open when the treads and risers are flexed in band-like form, so as to move in a substantially straight path and to 30 close when the treads and risers are flexed to assume a step-like form, so as to move in a spiral path.

The nature and scope of my present invention will be more fully understood from the 35 following description, taken in connection with the accompanying drawings, forming part hereof, in which—

Figure 1 is a top or plan view of a portion of a moving spiral stairway or elevator, one 40 portion of the treads and risers of which being shown as flexed to assume a step-like form, so as to move in a spiral path, and another portion being shown as flexed to assume a belt-like form, so as to move in a straight or sub- 45 stantially straight path, the whole so arranged embodying main features of my said invention. Fig. 2 is a detail view, enlarged, illustrating in top or plan view the segmental treads connected by divided or sectional risers, 50 wings, and clips connected with one section

of each of the risers and a railing arranged on each of the treads. Fig. 3 is a front elevational view of Fig. 2, and Fig. 4 is a central sectional view of one of the segmental treads.

Referring to the drawings, *a* is a tread of 55 segmental shape in plan, and *b* a riser consisting of two sections *b'* and *b''*, each of which, by means of hinges *b'*, is movably connected with a segmental tread *a*. The sections *b'* and *b''* at their outer ends are pivotally connected with each other by a hinge *b'* to permit the same to open and to close in a manner as shown, for example, in Figs. 1 and 2. A series of alternate treads *a* and risers *b* form the steps of the moving stairway, which may 60 be flexed into belt form or step form by means not shown. Each of the treads *a* is provided at its outer end with a roll or wheel *a'*, riding on a rail *c*, and at its inner end with a roll *a''*, engaging a channel-iron *d*, secured to a drum 65 *e*, which forms the guide for the roll *a''*, for a purpose fully described in my previous patent, No. 723,325. In addition to the roll *a''* each tread *a* is provided with a downwardly-projecting arm *a'*, carrying a roller *a''*, which by 70 engaging the channel-iron *d* assists in holding the tread *a* in a horizontal position when ascending or descending a spiral path, as shown in the upper portion of Fig. 1. When, however, the treads *a* are moved over a straight 75 portion arranged at the upper and lower landings of the spiral stairway, (partially shown in the lower part of Fig. 1,) the same are supported, preferably, by rollers *a''*, carried by brackets *a''*, secured to the under side of the 80 tread *a*, as shown in Figs. 3 and 4. The risers *b*, however, are supported by rollers *f*, preferably secured to the hinge *b'*, which in the 85 spiral path of the stairway travel on the rail *c*. Secured to the shaft *a'* of each of the rollers *a''* and in front of the same is arranged a grip *g* for a cable *h*, which is adapted to actuate the treads *a* and risers *b*, flexed into step-like form over the spiral path shown in the 90 upper part of Fig. 1. When in step-like form, 95 the sectional riser *b* is closed. Its sections *b'* and *b''* abut against each other, as shown at *b''* in Fig. 1. In this closed position the sections are stiffened and held in alinement with each other in addition to the hinge *b'* by a clip 100

i, secured to the section b^2 , and a wing k , secured to the section b' and engaging a guide-piece k' , secured to the section b^2 , as shown in Figs. 1 and 2. In the step-like form the 5 risers b assume a vertical position so as to permit the treads a to travel around the drum e . If, however, the straight portion a^{10} of a landing is reached, the treads a and risers b are stretched out into a belt-like form before 10 reaching such portion, as shown in Fig. 1. In this instance the risers are first flexed from a vertical position to a horizontal position and are held closed, as shown at b^{10} in Fig. 1. The more the risers b approach the substantial 15 straight portion a^{10} of the stairway the more the same will open to permit the treads a to be guided to and travel in a substantially straight path. When the treads a and risers b have reached the substantially straight portion a^{10} , the sections b' and b^2 of the risers b 20 will have opened to their fullest extent. The openings so formed are partially closed or bridged by the wings k . If a person should remain standing on a tread a when the same 25 is traveling in a straight path, the railing m will prevent the person so standing thereon stepping into the opening beyond the wing k , because the railing is arranged to follow the outline of the tread a up to the wing k and 30 curves or is rounded at the inner end of the tread, as illustrated in Fig. 2. Each of the treads a , in addition to the wheel a' , is provided with a wheel a^8 , carried by a bracket a^9 . This bracket is secured to the under side near 35 the inner end of the tread a , thereby assisting in the supporting of the tread in its travel in a spiral path.

Having thus described the nature and object of my invention, what I claim as new, and desire to secure by Letters Patent, is—

40 1. An elevating-conveyer or moving stairway, comprising treads and risers hinged together, each riser being formed of sections hinged at one end.

2. An elevating-conveyer or moving stairway, 45 comprising treads and risers hinged together, so as to be flexed into step-like and belt-like form, each of said risers being formed of two sections in pivotal connection at one end.

3. In an elevating-conveyer or moving stairway, a series of treads and risers hinged together, each of said risers being formed of two sections hinged at one end so as to permit said treads and risers to travel in curved 55 and substantially straight paths.

4. An elevating-conveyer or moving stairway, comprising treads and risers hinged together, each of said risers being formed of sections hinged at one end so as to close and open 60 when traveling in respectively curved and substantially straight paths, and means adapted to bridge the opening formed between the sections of said risers.

5. In an elevating-conveyer or moving 65 stairway, a series of treads and risers hinged together, each of said risers being formed of sections hinged at one end so as to close and open when said treads are traveling in curved and substantially straight paths, means adapted 70 to stiffen the sections of the risers when in a closed position, and one of said means adapted to bridge the opening formed between the sections of said risers.

6. In an elevating-conveyer or moving 75 stairway, a series of treads and risers hinged together, each of said risers being formed of sections pivotally connected at one end, in combination with a railing arranged on each of said treads.

In testimony whereof I have hereunto set my signature in the presence of two subscribing witnesses.

LEAMON G. SOUDER.
